UNITED STATES PATENT OFFICE.

GEORGE M. HALL, DECEASED, LATE OF BAIRD, TEXAS, BY ALZIRA C. HALL, EXECUTRIX, OF BAIRD, TEXAS.

HYDRANT BOX AND LID.

Application filed November 10, 1921. Serial No. 514,427.

To all whom it may concern:

Be it known that (Mrs.) ALZIRA C. HALL, a citizen of the United States, residing at Baird, in the county of Callahan and State 5 of Texas, executrix of the last will and testament of GEORGE M. HALL, late a citizen of the United States, resident of Baird, county of Callahan, and State of Texas, deceased, avers that the said GEORGE M. HALL 10 invented new and useful Improvements in Hydrant Boxes and Lids, of which the following is a specification.

This invention relates to a safety self-closing water hydrant box lid particularly 15 adapted for use in railroad yards and between track rails, as the ordinary hydrant box, for the purpose of supplying car tanks of various types with water.

The primary object of the invention is to 20 provide a water hydrant box of the class specified with a lid that may be readily opened for hydrant box service, and to so hinge the lid that it can be opened only to a certain angle, and when released, will automatically fall and close the box, and thereby prevent the lid from remaining open 25 and producing a dangerous projection.

To accomplish the foregoing object and to subserve the advantages incident to the 30 improvement, the hinge of the lid of the box consists essentially of a hinge bolt having in vertical alinement below the same a cross stop bolt or rod that will limit the opening movement of the lid, or dispose the same at such angle that it will fall without requiring manual attention. It is proposed to make the parts of the box partially of wood and of metal, or metal or wood throughout, or in accordance with boxes of 35 this type as now ordinarily constructed and used. Furthermore, the box may be of any preferred shape and is not limited to exact contour, yet it is preferred that the same be rectangular in general outline.

40 In the drawings:

Fig. 1 is a longitudinal vertical section of the improved device taken on the line 1—1 of Fig. 2 and showing the lid member elevated or open;

Fig. 2 is a top plan view of the improved 50 device;

Fig. 3 is a longitudinal vertical section on the line 3—3 of Fig. 4, showing the lid or cover open and illustrating a modification 55 of the improved device;

Fig. 4 is a top plan view of the modified structure shown by Fig. 3;

Fig. 5 is a transverse vertical section through the rear end of the box, showing a further modification, the lid or cover being open.

The numeral 5 in all of the figures of the drawings designates a box of suitable dimensions and of the form usually adopted in water hydrant boxes for railroad service, or for installation in various parts of railroad yards or between the tracks, the box being adapted to enclose the supply terminal of a water pipe that usually has a valve of a type that may be readily manipulated to give a supply of water therefrom and to shut off the water after a proper interval. The box or body 5 may be of metal or wood, or any other material adapted for the purpose, and as heretofore indicated, the essential feature of the invention consists of a lid or cover 6 which as shown by Figs. 1 and 2 is made in two sections 7 and 8. As shown by Figs. 3, 4 and 5, the lid or cover 9 is of one piece, 65 both forms of the lid or cover snugly fitting within and intended to fully close the upper end of the box or body 5.

In the form of the improved device shown by Figs. 1 and 2, the sections 7 and 8 of the 70 lid or cover have a metal clip bar 10 extending across the lower side adjacent to the rear edge and held against the said side of the lid or cover by bolts or other analogous fastenings 11. The sections 7 and 8 as shown by Fig. 1 near the rear edges thereof are formed with alined grooves or recesses 12, which open through the lower sides of the said lid or cover sections and are closed by the clip 10, the latter serving also 75 as a metal wear device. The grooves or recesses 12 are engaged by a pivot or fulcrum bolt or rod 13 extending transversely through the upper portion of the box or body near the rear end wall of the latter, 80 and vertically disposed below the bolt or rod 13 is a stop bolt or rod 14, which also extends transversely through the upper portion of the box or body 5. Adjacent to the front end of the box or body 5 a transverse 85 supporting bolt or rod 15 is inserted transversely through the upper portion of the device to serve as a means for supporting the free or unhinged front end of the lid or cover 6. Near the free end of the lid or 90 cover 6. Near the free end of the lid or 95 cover 6. Near the free end of the lid or 100 cover 6. Near the free end of the lid or 105 cover 6. Near the free end of the lid or 110 cover 6.

cover 6 and secured against the underside thereof by bolts or analogous fastenings 16 is a metal strip 17 extending fully across the sections and serving as a weight means 5 for insuring a drop or fall of the lid or cover when the latter is released. In view of the weight strip 17 the sections 7 and 8 have a central opening 18 formed therein, to facilitate raising the lid or cover by the 10 insertion in the said opening of a suitable implement adapted for the purpose.

In the form of the device shown by Figs. 3 and 4 the lid or cover is shown as having less thickness, and secured to the underside thereof on opposite sides of the longitudinal center are fulcrum brackets 19 which have alined openings 20 therethrough, for the reception of a transverse pivot or fulcrum bolt or rod 21, and the rear ends 20 of said brackets 19 are recessed or stepped, as at 22, to bear upon a stop rod 23 positioned similarly to the rod 14 heretofore described and serving the same purpose. In the upper portion of the front of the 25 box or body 5 a transverse stop or rest rod 24 is transversely inserted through the sides of the box and is exposed for engagement by the front end of the lid or cover 9 when the latter is closed. The lid or cover 30 9 in the form of the device shown by Figs. 3 and 4 also has a central opening 25 similar to the opening 18, for facilitating the opening operation of the lid or cover 9.

In the form of the device shown by Fig. 35 5, the rear end of the lid or cover 9 has a transverse opening 25 formed directly therein, to receive a transversely extending pivot bolt or rod 26, similar in all respects to the rods or bolts 13 and 20 heretofore described, and below the rod 25 in the form of the device shown by Fig. 5 and in vertical alinement therewith is a stop or check bolt or rod 27, to serve the same purpose as the rods 14 and 23 used in the forms of the 40 device illustrated by Figs. 1 to 4, inclusive.

The improved box in all its forms has a similar operation. When the lid or cover 50 of either form of the box is raised, it is prevented from being thrown back or rearwardly of a vertical plane through the pivot bolt or rod for the lid or cover by the stop or check rod 23, and the latter is so disposed relatively to the pivot bolt or rod that the lid or cover in each instance will 55 be held at a forward angle of inclination, or be poised in such manner that it will in-

stantly fall when released and automatically close the box or body 5. This disposition of the lid or cover in the several forms of the hydrant box will prevent accidents that 60 might ensue if the lid or cover was permitted to stand upwardly, or by neglect after use remain open. It is obvious that there is no possible way of overcoming the 65 tendency of the improved lid or cover to at all times automatically close when released, and during the time that the hydrant box and the water connections therein are in service, or used for supplying water to tanks or receptacles in cars, the lid or cover 70 will be held open, and after disconnection of the pipe connections from the hydrant or box, the lid or cover will assume its normal closed position.

The improved water hydrant box with the 75 automatically closing lid may be manufactured at a comparatively small cost, and in view of the advantages of the gravitating lid or cover, the additional cost that may be necessary to equip the hydrant box 80 with the improvement will be negligible when compared with the aversion of accidents incident to a lid or cover of hydrant boxes of this character that may be allowed to remain open or have to be manually closed 85 after use.

What is claimed as new is:

1. A hydrant box of the class specified, comprising a lid or cover, a pivot rod for the lid or cover, and a stop rod disposed 90 vertically below the pivot rod and serving to prevent the lid or cover being opened rearwardly beyond a predetermined distance and insure an automatic gravitating closure of the lid or cover when released. 95

2. A hydrant box of the class specified, having a lid or cover provided with a pivot device, and a stop rod extending across the box in vertical alinement with and below the pivot device of the lid or cover to engage a part of the latter adjacent to the rear edge thereof. 100

In testimony whereof I have hereunto set my hand in presence of two subscribing witnesses.

Mrs. ALZIRA C. HALL,
Administratrix of the estate of George M.
Hall, deceased.
